DESCRIPTION

FIG. 1 is a perspective view of a HVACR enclosure according to a first embodiment,
 FIG. 2 is a front view thereof,
 FIG. 3 is a rear view thereof,
 FIG. 4 is a left side view thereof,
 FIG. 5 is a right side view thereof, and
 FIG. 6 is a top view thereof.
 FIG. 7 is a perspective view of a HVACR enclosure according to a second embodiment,
 FIG. 8 is a front view thereof,
 FIG. 9 is a rear view thereof,
 FIG. 10 is a left side view thereof,
 FIG. 11 is a right side view thereof, and
 FIG. 12 is a top view thereof.
 FIG. 13 is a perspective view of a HVACR enclosure according to a third embodiment,
 FIG. 14 is a front view thereof,
 FIG. 15 is a rear view thereof,
 FIG. 16 is a left side view thereof,
 FIG. 17 is a right side view thereof, and
 FIG. 18 is a top view thereof.
 FIG. 19 is a perspective view of a HVACR enclosure according to a fourth embodiment,
 FIG. 20 is a front view thereof,
 FIG. 21 is a rear view thereof,
 FIG. 22 is a left side view thereof,
 FIG. 23 is a right side view thereof, and
 FIG. 24 is a top view thereof.
 FIG. 25 is a perspective view of a HVACR enclosure according to a fifth embodiment,
 FIG. 26 is a front view thereof,
 FIG. 27 is a rear view thereof,
 FIG. 28 is a left side view thereof,

FIG. 29 is a right side view thereof, and
 FIG. 30 is a top view thereof.
 FIG. 31 is a perspective view of a HVACR enclosure according to a sixth embodiment,
 FIG. 32 is a front view thereof,
 FIG. 33 is a rear view thereof,
 FIG. 34 is a left side view thereof,
 FIG. 35 is a right side view thereof, and
 FIG. 36 is a top view thereof.
 FIG. 37 is a perspective view of a HVACR enclosure according to a seventh embodiment,
 FIG. 38 is a front view thereof,
 FIG. 39 is a rear view thereof,
 FIG. 40 is a left side view thereof,
 FIG. 41 is a right side view thereof, and
 FIG. 42 is a top view thereof.
 FIG. 43 is a perspective view of a HVACR enclosure according to an eighth embodiment,
 FIG. 44 is a front view thereof,
 FIG. 45 is a rear view thereof,
 FIG. 46 is a left side view thereof,
 FIG. 47 is a right side view thereof, and
 FIG. 48 is a top view thereof.
 FIG. 49 is a perspective view of a HVACR enclosure according to a ninth embodiment,
 FIG. 50 is a front view thereof,
 FIG. 51 is a rear view thereof,
 FIG. 52 is a left side view thereof,
 FIG. 53 is a right side view thereof, and
 FIG. 54 is a top view thereof.
 FIG. 55 is a perspective view of a HVACR enclosure according to a tenth embodiment,
 FIG. 56 is a front view thereof,
 FIG. 57 is a rear view thereof,
 FIG. 58 is a left side view thereof,
 FIG. 59 is a right side view thereof, and
 FIG. 60 is a top view thereof.
 FIG. 61 is a perspective view of a HVACR enclosure according to an eleventh embodiment,
 FIG. 62 is a front view thereof,
 FIG. 63 is a rear view thereof,
 FIG. 64 is a left side view thereof,
 FIG. 65 is a right side view thereof, and
 FIG. 66 is a top view thereof.
 FIG. 67 is a perspective view of a HVACR enclosure according to a twelfth embodiment,
 FIG. 68 is a front view thereof,
 FIG. 69 is a rear view thereof,
 FIG. 70 is a left side view thereof,
 FIG. 71 is a right side view thereof, and
 FIG. 72 is a top view thereof.
 FIG. 73 is a perspective view of a HVACR enclosure according to a thirteenth embodiment,
 FIG. 74 is a front view thereof,
 FIG. 75 is a rear view thereof,
 FIG. 76 is a left side view thereof,
 FIG. 77 is a right side view thereof, and
 FIG. 78 is a top view thereof.
 FIG. 79 is a perspective view of a HVACR enclosure according to a fourteenth embodiment,
 FIG. 80 is a front view thereof,
 FIG. 81 is a rear view thereof,
 FIG. 82 is a left side view thereof,
 FIG. 83 is a right side view thereof; and,
 FIG. 84 is a top view thereof.
